UNITED STATES PATENT OFFICE.

EDWARD SHIELDS, OF BRADDOCK, PENNSYLVANIA; BRADDOCK TRUST CO., OF BRADDOCK, PENNSYLVANIA, ADMINISTRATOR OF SAID EDWARD SHIELDS, DECEASED.

LOOSE-LEAF BINDER.

1,331,588.

Specification of Letters Patent.

Patented Feb. 24, 1920.

Application filed April 29, 1918. Serial No. 231,326.

To all whom it may concern:

Be it known that I, EDWARD SHIELDS, a citizen of the United States, residing at Braddock, Allegheny county, Pennsylvania, 5 have invented a new and useful Improvement in Loose-Leaf Binders, of which the following is a full, clear, and exact description, reference being had to the accompanying drawing, forming part of this specification, in which—

Figure 1 is a transverse section showing my improved binder, the section being taken through the binding strips.

Fig. 2 is a section on the line II—II of 15 Fig. 1.

Fig. 3 is a plan view of the top binding strip with one of the clutch devices removed, and

Fig. 4 is a bottom plan view of one of the 20 clutch devices detached from the binding strip.

My invention has relation to loose-leaf binders; and is designed to provide a binder of simple and convenient character and 25 which can be readily operated.

The nature of my invention will be best understood by reference to the accompanying drawing in which I have shown a preferred embodiment thereof, and which will 30 now be described, it being premised, however, that various changes can be made in the details of construction and arrangement of the parts without departing from the spirit and scope of my invention as pointed 35 out in the appended claims.

In this drawing, the numeral 2 designates the upper cover of a loose-leaf binder and 3 the lower cover, these covers being flexibly or otherwise hingedly connected respectively 40 to the top binding strip 4 and lower binding strip 5 in any suitable or usual manner. 6 designates vertical posts which are firmly secured on the lower binding strip 5. In the drawing I have shown two of these posts

45 which will be sufficient for ordinary sizes of binders, although it will be understood that a greater number may be employed, if desired. The top binding strip 4 is provided with apertures 7 to receive the respective posts. Said binding strip is also provided with a plurality of clutch devices, one for each post. The clutch members 8 are each pivotally supported on the top binding strip by means of a rivet 11 which 55 is loosely secured in said strip and which

loosely engages the rivet opening in the clutch member. The clutch member 9 is secured to the spring 10 by a rivet 12, this spring forming the only support for said member 9. The spring is fixedly secured 60 at one end to the top binding strip by means of a rivet 13 and is secured to the clutch member 8 by a rivet 14. One end portion of the clutch member 8 is bent upwardly, as indicated at 8^a, to form a finger 65 press-plate for releasing the clutch members. The two clutch members of each clutch device are arranged upon opposite sides of the post, their adjacent ends being provided with approximately semi-circular notches 15. 70

The springs 10 normally hold the clutch members in their lowered positions, in which they effectively grip the respective posts and thus firmly secure the binding strip. When it is desired to release the clutches, 75 75 the finger press portions 8^a are depressed, thereby releasing the grip of the clutch members and enabling the top cover with its binding strip to be readily removed from the posts.

The advantages of my invention result from the simplicity of the construction and arrangement of the clutch members and their mode of operation. The nature of the locking action is such as to exert little or 85 no strain on the posts, and not of a character tending to spread or bend them or to tear or destroy the bound leaves or sheets. 80

I claim:

1. A loose leaf binder comprising a binding member having a post, an opposed binding member having an aperture to receive said post, a spring secured to the member having the aperture, and a pair of clutch members arranged to clutch the post from 95 opposite sides carried by said spring and normally held thereby in clutching engagement with the post, substantially as described.

2. A loose-leaf binder, comprising a lower 100 binding member having a plurality of posts rigidly secured thereto, an upper binding member having an aperture for each of said posts, and clutch devices for each post carried by the upper member, each of said devices comprising spring-supported clutching members adapted to engage opposite sides of the posts, substantially as described. 105

3. In a loose-leaf binder, the combination 110 with a binding strip having an aperture

therethrough, a clutch member pivoted to said strip at one side of said aperture, an opposing clutch member at the opposite side of said aperture, and a spring secured to the strip and to both the clutch members, substantially as described.

4. In a loose-leaf binder, the combination with a binding strip having an aperture therethrough, a clutch member pivoted 10 to said strip at one side of said aperture, an

opposing clutch member at the opposite side of said aperture, and a spring secured to the strip and to both the clutch members, the pivoted clutch member having an upwardly bent portion forming a finger plate for releasing the clutch action of said members, substantially as described. 25

In testimony whereof, I have hereunto set my hand.

EDWARD SHIELDS.
